UNITED STATES PATENT OFFICE.

MOTT X. CORCORAN, OF VALPARAISO, INDIANA.

FLASH-LIGHT METER.

1,287,241.

Specification of Letters Patent. Patented Dec. 10, 1918.

Application filed October 22, 1915. Serial No. 57,235.

To all whom it may concern:

Be it known that I, MOTT X. CORCORAN, a citizen of the United States, and a resident of the city of Valparaiso, in the county of

5 Porter and State of Indiana, have invented certain new and useful Improvements in Flash-Light Meters; and I do hereby declare that the following is a full, clear, and exact description of the same, reference being had to the accompanying drawings, and to the numerals of reference marked thereon, which form a part of this specification.

In photography, the required time of exposure is governed by a number of conditions such as the lighting of the object to be photographed, the size of the diaphragm opening, the rapidity of the plate or film and the character of the lens, all of which make it very difficult for an inexperienced

20 photographer to take good pictures.

In flashlight photography, the timing of the exposure is accomplished by varying the quantity of flashlight substance employed and in determining the quantity of flashlight substance to be used, it is necessary to take into consideration the efficiency of the flashlight substance, the size of the diaphragm used, the rapidity of the plate or film, the speed of the lens, etc., and the 25 quantity of flashlight substance used must be varied accordingly in order to give the proper degree of illumination for taking the picture. It is usually rather difficult particularly for an amateur to determine or 30 measure the required quantity of flashlight substance on account of the variations in the quantity required because of the above conditions, and also because the quantity of flashlight substance required does not vary 35 in direct proportion to the distance of the object from the camera.

It is an object of my invention to provide means which can be readily understood and used by an ordinary amateur photographer for determining the quantity of flashlight substance required under various 40 conditions.

Another object of my invention is to provide a means for measuring flashlight substances which is marked to indicate the 45 quantity of flashlight material to be used under normal conditions for various distances.

Another object of my invention is to provide means for measuring flashlight substances which shows the quantity of flash-

light substance to be used for each diaphragm opening under normal conditions for the various distances.

Another object of the invention is to provide a means for measuring flashlight substances having a scale for determining the quantity of flashlight substance to be used under normal conditions at various distances and to provide in coöperative relation with the said scale, another scale for correcting the measurement of the quantity of flashlight material to be used to accord with conditions which vary the effectiveness of the flash.

Another object of the invention is to provide in connection with a flashlight measuring device, having a scale for measuring the quantity of flashlight material to be used, a magazine which does not enlarge the measuring device and which comprises a supplemental holder from which a supply of flashlight substance contained therein can be poured into the measuring device.

Other and further important objects of my invention will be apparent from the disclosure in the specification and drawings.

The invention (in a preferred form) is illustrated in the drawings and hereinafter more fully described.

In the drawings:

Figure 1 is a side elevation of a device embodying the principles of my invention shown closed and in zero position.

Fig. 2 is a similar view thereof partly broken away, illustrating the same in an adjusted position with parts removed.

Fig. 3 is a view of a detached member of a modified form of device.

Fig. 4 is a view somewhat similar to Fig. 2, showing a quantity of powder being measured.

Fig. 5 is a sectional view of the form of device illustrated in Fig. 1.

Fig. 6 is a development view of the scale member shown in Figs. 1, 2, and 4.

Fig. 7 is an end view of the device shown in Fig. 2.

Fig. 8 is a section taken on line 8—8 of Fig. 5.

Fig. 9 is a similar section of a modified form of device.

Fig. 10 is a similar section of another modified form of device.

Fig. 11 is a similar section of still another modified form of device.

Fig. 12 is a development view illustrating

another arrangement of indicating and computing scales.

Fig. 13 is a view similar to Fig. 12, of another type of indication scale.

Fig. 14 is an elevation of a measuring container with a uniformly graduated distance scale thereon.

As shown in the drawings:

The device consists of a tubular shell or 10 casing, open at both ends, indicated by the reference numeral 1, and in the present instance shown rectangular in cross section, (though of course the section may be of any shape desired) and said shell may be constructed of any suitable material, such as 15 paper, fiber, or metal. Slidably in said rectangular shell 1, and frictionally held from accidental movement therein, is a rectangular graduated element 2, which may 20 be solid or hollow, as desired, but in either event closed at one end, and of a length, as clearly shown in Fig. 1, slightly greater than the tubular shell, so as to project beyond the same at the lower end thereof.

25 As clearly shown in Figs. 1, 2, 4, 5, and 7, the movable element 2, has four side walls, each one of which is graduated, the graduations on each of three of the scales representing distances in feet from flash to subject for a certain diaphragm opening noted below the scale both in the "f" and "U.S." systems. Inasmuch as the illumination of the subject varies reversely as the square 30 of the distance of the flash from the subject, a simple proportion does not exist between the quantities of substance required and distance of the source of light from the subject, so that in order to properly measure the substance it is necessary that the scales 35 representing the distances be laid out according to certain curve equations. This is in order that the proper increments of movement of the element 2, within the shell 1, may be obtained to afford a compartment 40 of the proper dimensions at the upper end of the device into which the substance, denoted by the letter X, is poured for measurement.

As shown in the development view in 50 Fig. 6, the first scale represented is for a diaphragm opening of "f.16" or "U.S.16," which is a comparatively small aperture. The next scale is graduated for a diaphragm stop of "f.11.3" or "U.S.8," and this stop 55 opening is twice the area of the "f.16" or "U.S.16" stop, and of course admits twice as much light. Consequently the distance scale for the "f.11.3" or "U.S.8" stop differs from the first scale in that the graduations 60 representing the distances in feet are only one half as far apart, and the volume of the compartment formed at the top of the device to receive the powder measured, is only one half as great for a given distance 65 as that for the first scale. Similarly on

the distance scale calculated for diaphragm stops "f.8" and "U.S.4" the area of opening of which is twice as large as that of the preceding stop, and four times as large as that of the "f.16" and "U.S.16" stop, the 70 graduations representing the distances are only one half as far apart as those on the second scale, and only one fourth as far apart as those on the first scale. Of course the volume of the measuring compartment 75 formed at the top of the device, figured by the third described scale, varies accordingly, being either one half or one fourth as large, as the case may be. That is to say, for a given distance, say twenty feet of the source 80 of light from the subject, by using the first scale a certain volume of powder is necessary, and using the second scale, that is with a larger diaphragm opening, only half as much powder is necessary, and using the 85 third scale, that is with a diaphragm opening four times as large, only one fourth the quantity of flash substance is required.

The fourth scale shown has even graduations numbered similarly to the other 90 scales, from the bottom of the insert 2, and is useful for calculating corrections, to be made on account of certain conditions, to the quantity of flashlight material as determined by the other scales. 95 For instance, setting the element 2, for eighteen feet on the "U.S.8" scale, a corresponding reading of "18" would be obtained upon the factorial scale. If the particular kind or quality of the flash substance to 100 be used has only one half the illuminating power or intensity for which the distance scale for "U.S.8" stop is calculated, it will be necessary to use twice the amount of flashlight substance. The other scales have 105 uneven graduations and cannot readily be used for proportionate adjustments and for this reason the factorial scale is provided. In the illustration stated the factorial scale setting "18" is multiplied by two, giving 110 "36" and the factorial scale is then set to "36" and this will give the proper volume at the upper end of the device for the required quantity of flash substance to be used. On the other hand for the same setting, that is eighteen feet on the "U.S.8" scale, supposing a plate or film is to be used which is twice as fast as that for which the distance scale is calculated, then the factorial scale reading "18" must be divided 115 by two, and the movable element 2 is adjusted for such a reading on the factorial scale, so that the compartment formed at the upper end of the device is of the proper size to measure the necessary quantity of 120 flash required for the picture.

It is obvious that a number of corrective factors may be multiplied into one another to obtain new readings on the factorial scale, and the movable element 2, is then finally set 130

according to the new reading obtained, irrespective of the readings on the distance scales, the same merely being used for an initial setting to obtain an initial reading on the factorial scale for a given set of conditions. It is clearly obvious that the factorial scale may have a number of applications for the computation of corrections depending on many different conditions.

10 In the sectional view of the device illustrated in Fig. 5, I have shown, as before, a rectangular tubular shell or casing 3, the movable element being denoted by the reference numeral 4, and consisting of a rectangular tube closed at its upper end and open at its lower end and slightly greater in length than the shell 3, and provided with a scale as before. Inserted within said element 4, at the lower end thereof, is another 15 tubular member 5, which fits tightly therein, and may contain a quantity of flash powder Y. Thus in using the device the movable element 4, is set to the proper indicating mark on one of its scales, and the tubular 20 container 5, is withdrawn and a certain quantity of the powder therein emptied into the compartment formed at the upper end of the device, to fill the same and thus obtaining the quantity of powder required.

25 Of course if so desired the device may be made hexagonal, as shown in Fig. 9, or cylindrical, as shown in Fig. 10, wherein the outer shell is denoted by the reference numeral 6, the adjustable tubular scale carrying member by the reference numeral 7, and the flashlight powder container by the reference numeral 8. In Fig. 11, I have illustrated a modified form of device for measuring flashlight strips which may be furnished in different lengths of a certain width, and the proper quantity or length required may be readily obtained by projecting or inserting the end of the sheet into the envelop or container 9, when the indicating card or movable element 10, therein 30 has been moved to an adjusted position for a certain setting on the distance scale provided. Instead of actually inserting the flashlight strip therein for measurement, the 35 scale on the movable member may denote in inches or other unit lengths, the proper amount or length of flashlight sheet necessary, and a measuring scale may be laid off on the movable member 10, by which the 40 sheet may be measured off.

In the modified form of device illustrated in Fig. 12, I have shown a development view of a movable member 11, provided with curves for certain distances, one curve being 45 provided for each distance selected. The points at which these distance curves cut the parallel vertical lines representing the diaphragm openings are points for setting the movable member in the container for obtaining a proper volume of flash powder. The

development view also shows a factorial scale with convergent lines drawn thereacross for graphically computing a new result where a factor greater or less than 1, is introduced for consideration. The main 70 factorial scale is graduated along the vertical "1" line similarly to that described with reference to Fig. 6, and on each side of the "1" line are parallel lines representing factors greater than 1, to-wit 2, $1\frac{1}{4}$, $1\frac{1}{2}$, $1\frac{3}{4}$, and $\frac{3}{4}$, 75 $\frac{1}{2}$, and $\frac{1}{4}$. The convergent lines cut the vertical lines proportionate distances apart, so that if the factorial scale reads "10" and the factor to be multiplied thereinto is " $\frac{1}{2}$ ", the convergent line cutting the "1" line at 80 "10" is traced along until the point at which it cuts the " $\frac{1}{2}$ " line is found and this point which will correspond to "5" on the "1" line is the proper setting for the movable member.

85 In Fig. 13 in place of using curves to ascertain the various points on the scales, I have laid off the divisions on a movable element 12, both on the distance and factorial scales, and printed the actual computed numerical values at the different points. Fig. 14 represents a transparent container 13, of varying cross sectional area, for measurement of flash powder with a distance scale graduated thereon, the graduations of which, 90 due to the shape of the container, are spaced 95 equidistantly apart.

100 It is obvious that other scales may be provided upon the movable member, for instance solar scales for use in daylight work for the determination of different factors to be considered with certain ones given. A similar device may be readily constructed for the measurement of magnesium ribbon, that is to say a scale may be calculated and 105 described upon the movable element 2, of the form of device first described to give the required length of ribbon necessary for a given distance from the source of light to subject and a given diaphragm opening. It is obvious also that my invention is capable of a 110 converse use, that is, for the determination of proper distances between flash and subject for a given or predetermined quantity of powder. Then, too, my invention may be 115 readily combined with instruments or mechanisms for actually measuring the distance between the subject and flash without departing from the principles of my invention.

I am aware that various other details of 120 construction may be varied through a wide range without departing from the principles of my invention, and I therefore do not purpose limiting the patent granted otherwise than necessitated by the prior art.

125 I claim as my invention:

1. A container for measuring flashlight material for photographing purposes, comprising a member having a distance indicating scale and having means cooperating with 130

- the said scale member for varying the capacity of the container, the said scale member being graduated so that when the said means is adjusted to indicate on the scale the distance between the flash and the object to be photographed, the container will measure the amount of flashlight material required for taking the picture at the distance indicated by the scale.
- 10 2. A container for measuring flashlight material, comprising a member having a plurality of different distance indicating scales, each suitably marked to correspond with the designation of a diaphragm opening of a photographing machine, said container having means coöperating with the said scale member, for varying the capacity of the container, the said scale member being graduated so that when said means is adjusted to indicate on the scale the distance between the flash and the object to be photographed, the container will measure the amount of flashlight material required for taking the photograph at the given distance.
- 15 3. A container for measuring flashlight material for photographing purposes, comprising a member having a main scale and an auxiliary scale and having means co-operating with the said scale member for varying the capacity of the container, the said main scale consisting of uneven distance indicating graduations coöperating with the said means so that when the said means is adjusted to indicate on said scale the distance between the flash and the object to be photographed, the container will hold the quantity of flashlight material required at the said distance and the said auxiliary scale consisting of even graduations for proportional adjustment of the volume of the container.
- 20 In testimony whereof I have hereunto subscribed my name in the presence of two subscribing witnesses.

MOTT X. CORCORAN.
